UNITED STATES PATENT OFFICE.

ELMER E. WIGHTMAN, OF CHICAGO, ILLINOIS.

DENTAL CASTING-MACHINE.

1,230,254.

Specification of Letters Patent. Patented June 19, 1917.

Application filed March 10, 1916. Serial No. 83,258.

To all whom it may concern:

Be it known that I, ELMER E. WIGHTMAN, a citizen of the United States, and a resident of the city of Chicago, in the county of Cook and State of Illinois, have invented certain new and useful Improvements in a Dental Casting-Machine; and I do hereby declare that the following is a full, clear, and exact description of the same, reference being had to the accompanying drawings, and to the numerals of reference marked thereon, which form a part of this specification.

Difficulty has been experienced heretofore in the use of dental casting apparatus by which metallic inlays for teeth are formed, owing to the multiplicity of operations necessary during the process of molding the inlay or other article, as the case may be. This invention relates to an improved type of casting apparatus wherein the number of operations necessary on the part of the person making the mold and casting the inlay is reduced to a minimum, so that the successful production of a casting is assured with a high degree of efficiency. Heretofore the multiplicity of operations which have been necessary, as for instance, the continuous pumping for creating a suction, have required so much of the time and attention of a person using the apparatus that the metal, particularly where gold has been used, has solidified prematurely and as a consequence liability of an imperfect casting is the result.

It is an object therefore of this invention to construct an improved type of dental casting apparatus wherein means are provided for creating a direct suction in a dental mold to facilitate the casting operation and insure the formation of a substantially perfect product.

It is also an object of this invention to construct a dental apparatus adapted to operate efficiently in facilitating the production of a dental casting or inlay, wherein the number of operations on the part of the person using the apparatus is reduced to a minimum and the production of a successful inlay from the mold, assured.

It is furthermore an object of this invention to construct a dental apparatus comprising means to receive a small flask containing the mold sealingly mounted on said means, with a foot operated suction producing mechanism conveniently associated

therewith, and with mechanisms acting automatically when released to permit a strong suction effect upon the mold within the flask to facilitate entrance thereinto of a fused metal to be cast in the mold into an inlay or other article.

It is finally an object of this invention to construct an improved type of dental apparatus consisting of few parts and with the parts arranged for convenient operation, permitting work to be performed with the greatest degree of efficiency and minimum number of operations.

The invention (in a preferred form) is illustrated in the drawings and hereinafter more fully described.

In the drawings:

Figure 1 is a view partly in section and partly in elevation of the assembled parts of the apparatus embodying the principles of my invention.

Fig. 2 is a detail section taken on line 2—2 of Fig. 1.

Fig. 3 is a fragmentary detail section taken on line 3—3 of Fig. 2.

Fig. 4 is a detail section taken on line 4—4 of Fig. 1.

Fig. 5 is a view with parts in section, taken on line 5—5 of Fig. 4.

Fig. 6 is a sectional detail view of a modified form of flask for a different type of mold, capable of being used with my apparatus.

As shown in the drawings:

The reference numeral 1, indicates as a whole any suitable type of table or bench, and extending through the table or bench top is a pipe 2, held securely and rigidly therein and at its upper end provided with a rotary plug valve 3. A base plate 4, is secured upon the floor on which the table stands, and threaded thereinto and projecting upwardly therefrom are a pair of uprights 5. Secured to and supported upon the upper ends of said uprights 5, is a cylinder 6, the upper end of which receives threaded therein said pipe 2. Movable within said cylinder 6 is a piston 7, having secured thereto and extending downwardly therefrom a piston rod 8, which extends through the lower end of the cylinder and is pivotally connected to a foot pedal 9, slideable upon said uprights 5, and the forward end of which is provided with a rounded shoe 10, engaging movably beneath a roller 11, mounted in lugs at the forward end of the base plate 4. In order to resist

downward movement of said pedal 9, as well as said piston 7, within the cylinder, coiled tension springs 12, are connected on extensions on each side of the pedal 9, and to lugs provided at the upper end of the cylinder 6. The rotatable plug valve 3, is provided with an actuating handle or lever 13, connected on one end of which is a tension spring 14, having its other end connected to a fixed point in the top of the table or bench 1, and disposed to latch over the other end of said lever or handle 13, is a spring impelled pawl 15, pivotally mounted at the top surface of the table top and impelled forwardly by a leaf spring 16, mounted adjacent thereto.

Secured in the upper end of the valve 3, is a pipe section 17, having formed on the upper end thereof an enlarged cored out head, the exterior surface of which is ground to a conical taper 18, convergent upwardly, and the interior cored out portion of which is ground to a downwardly or inwardly convergent taper 19. Shown in Figs. 1 and 2, is a flask 20, having an interior perforated wall or partition 21, and with the lower end of the flask ground to a taper to fit sealingly over the exterior ground portion 18, of the pipe section leading from the valve 3. In Fig. 6, I have shown a modified type of flask denoted by the reference numeral 22, having a tubular lower stem extension 23, the exterior surface of which is ground to a taper adapted to fit into the interiorly ground tapered portion 19, of the pipe extension of the valve 3, to support the flask attached thereon in place of the flask 20, and of course in sealing relation thereon. A removable perforated partition element 24, is provided to seat upon a shoulder or ledge provided upon the interior of the flask 22, to receive the plaster of Paris 25, or other material of which the mold is made packed thereon within the flask. In the present instance the casting so formed in the mold is shown in section, being denoted by the reference numeral 26.

Means are provided for latching the pedal 9, in a depressed position against a suction created in the cylinder, as well as the stress of the springs 12, and for this purpose a pawl 27, is pivoted in the notched rear end of the base plate 4, and normally impelled forwardly by a leaf spring 28, and is adapted to project through and engage over the upper edge of an aperture 29, provided in the end of the pedal 9.

The operation is as follows:

In making a mold, the usual procedure is followed, that is, the material of which the mold is made, is packed into either one of the flasks 20 or 22, as the case may be, with the wax pattern therein, after which the mold is heated and the wax pattern melted away. The flask is then mounted upon the

pipe extension 17, and the globule of metal placed on the surface of the mold in a pocket provided therefor, as usual, and fused by means of a blowpipe or other means so that the fused metal may flow downwardly through a gate, into the mold. Just as this operation is about to take place, the valve 3, is opened from the position shown in Fig. 2, to release position by striking the latch 15, rearwardly to release the handle 13, of the valve, and the spring 14, acts under tension to rotate the valve suddenly into open position. This sudden movement of the valve is important, for the reason that a strong suction effect is exerted immediately upon the mold and the fused metal flows instantly thereto without possibility of premature solidification. The piston 7, in the cylinder 6, has of course been previously drawn downwardly into the lower end of the cylinder by depression of the pedal 9, and retained by the latching of said pedal with the pawl 27, so that the suction created in the cylinder 6, is exerted through the pipe 2, and open valve 13, upon the mold. The preliminary operations necessary for using the apparatus may be performed beforehand, that is, the valve 3, closed and the piston 7, drawn to the lower end of the cylinder and the pedal 9, latched in its lower position to thus maintain the suction created within the cylinder. It is then only necessary at the proper time in the process to release the latch 15, and permit the suction to be exerted through the porous material of the mold within the flask to evacuate the mold and insure an easy flow thereto of the molten or fused metal of which the casting is to be made.

The cylinder 6, is of relatively large capacity, so that only one stroke of the piston therein is necessary to create a sufficient suction for one casting operation, thus obviating the continuous pumping operations as in the case of pumps or other means used heretofore.

I am aware that various details of construction may be varied through a wide range without departing from the principles of this invention, and I therefore do not purpose limiting the patent granted otherwise than necessitated by the prior art.

I claim as my invention:

1. In an apparatus of the class described, a suction producing means, mechanism in communication therewith adapted to receive a mold flask sealingly attached thereto, a valve located therebetween, means for moving said valve to open position, and a latch adapted to retain said valve in closed position against the power of said moving means.

2. In an apparatus of the class described, a suction producing means, mechanism in communication therewith adapted to receive a mold flask sealingly attached thereto, a

valve located therebetween, a spring for moving said valve to open position, and a latch adapted to retain said valve in closed position against the tension of said spring.

5 3. In an apparatus of the class described, a suction pump, its piston, a treadle for operating said piston in one direction, springs for operating said piston in the return direction, a mold flask sealingly connected directly with said pump, and a quick operating valve self-opening when released to establish immediate communication between said pump cylinder and said flask.

10 4. In an apparatus of the class described,

a suction producing means, and a head connected thereto having its exterior surface tapered conically and converging upwardly and having its interior cored out in a downward converging taper, either of said tapered portions adapted to receive a mold 15 flask.

In testimony whereof I have hereunto subscribed my name in the presence of two subscribing witnesses.

ELMER E. WIGHTMAN.
